UNITED STATES PATENT OFFICE.

HARVEY B. KENNEDY, OF PITTSBURG, KANSAS.

ARCH SUPPORT.

Application filed September 27, 1920. Serial No. 412,898.

To all whom it may concern:

Be it known that I, HARVEY B. KENNEDY, a citizen of the United States, and resident of Pittsburg, county of Crawford, and State 5 of Kansas, have invented a certain new and useful Improvement in Arch Supports, of which the following is a complete specification.

This invention relates to arch supporting devices, and aims to provide an improved device for lending the proper support to the bony arch and muscles of the feet, for which purpose the device is designed to be worn inside of a shoe in position for exerting the 10 desired bracing and supporting action upon the arch and muscles of the foot.

Accordingly, one of the objects of the invention is to provide an improved form of arch support adapted to be worn inside 20 of a shoe and having means for adjustably supporting the arch of the foot and also for exerting any bracing action which may be necessary at either of the sides of the foot, together with means for exerting a corrective 25 action with reference to the metatarsal portion of the foot, or at either side of the heel portion of the foot.

To this end, I have devised an improved device which is made up of an insole member 30 provided with a flexible flap portion between which and the insole member is adapted to be removably inserted one or more filler elements for adjusting the height of the flap above the insole. In carrying out this feature of the construction, provision is made 35 for applying the filler elements to the under face of the flap and removably attaching said elements to said under face of the flap.

Another feature of the improved device 40 is the provision of a suitable form of pad or filler which is adapted to be inserted between the flap and insole member of the device in proper position for corrective action with reference to the metatarsal bones of 45 the foot.

For the purpose of applying the desired corrective action at either of the sides of the heel portion of the foot, I have devised an improved insole member having one or more 50 filler or brace elements which are adapted to be removably applied to the under face of said insole at either of the sides thereof, together with means for retaining the said elements in place in either of these relations.

55 With these general objects in view, the invention will now be described by reference

to the accompanying drawings, illustrating a practical form of construction for embodying the proposed improvement, after which the novel features and combinations 60 will be particularly set forth and claimed.

In the drawings,—

Figure 1 is a perspective view of an arch supporting device constructed in accordance with the present invention, and showing the 65 same in its proper relation to the inner-sole of a shoe, represented in broken lines, the flap portion of the device being shown in elevated position for disclosing the parts beneath;

Figure 2 is a plan view of the device, with the flap let down in normal position;

Figure 3 is a bottom plan view of the insole member of the device;

Figure 4 is an enlarged longitudinal central section, showing the device with various filler elements in position;

Figure 5 is a transverse section taken on the line 5—5 of Figure 4.

Figure 6 is a perspective view of the flap 80 member similar to the right hand portion of Figure 1, but showing one of the interior filler elements attached to said flap portion;

Figure 7 is a perspective view of the interior 85 filler element, such as is shown applied in position in Figure 6, and having loops for retaining engagement with another form of filler such as shown in perspective view in Figure 8;

Figure 9 is a central longitudinal section 90 view of a shoe and arch support embodying the present invention and illustrating the same in proper relation to a foot, shown in broken lines in said view;

Figure 10 is an enlarged detail sectional view of the pad layer structure;

Figure 11 is an inverted plan view of the device with one of the bottom pad or filler 100 elements applied thereto, the broken lines representing the said filler element shifted to the opposite side of the device in inverted position;

Figure 12 is an inverted plan view of the device showing another pad or filler element applied thereto, and with broken lines representing said element shifted to the opposite side of the device, as in the case of the filler element shown in Figure 11; and

Figure 13 is also an inverted plan view of 110 the device showing the same parts as Figure 12 with the addition of a second pad

or filler element applied to the first one in superposed relation.

Referring now to the drawings in detail, these illustrate the improved device as comprising an insole member 14 which is adapted to be inserted within the shoe 15 in engagement with the upper or interior face of the insole 16 of the shoe. The insole 14 is made from leather or any other suitable material having the requisite strength as well as flexibility, and is formed with the side wings or extension 17 for bracing the opposite sides of the foot at the arched portion thereof. The outside wing or extension 17 serves to retain and support the tarsal bones of the arch and also aids in supporting and bracing the outside metatarsal bone, while the inner wing or extension 17 lends support principally to the bony arch from the inner side of the foot. Preferably, the bottom face of the heel end of the insole 14 is buffed away somewhat to provide a suitable heel-seat portion 18 (see Figure 3) opposite the corresponding portion of the inner sole 16. To the opposite or forward end of the insole member 14, is secured, as by means of stitching 19, the forward edge of a flap member 20 of any suitable material such as leather or the like, and of a form and size adapted to overlie the insole 14 between its extensions or wings 17, as shown in Figure 2. To the interior or under face of this flap member 20 is secured as by means of stitching 21, a sheet of lining material 22 into which is cut transverse slits 23 near each end of said piece of lining 22, for the purpose of providing a pair of oppositely facing pockets 24, as is clearly illustrated in Figure 1. This pocket structure provides a pair of retaining pockets for the opposite ends of a pad or filler element 25 of a size adapted to be fitted into the relation shown in Figure 6, the opposite ends of said filler 25 being appropriately tapered for facilitating the insertion of said ends into the pockets 24 (see Figures 4 and 10). The pad or filler 25 is also provided with a facing 26 of suitable material which may be secured thereto by means of stitching 27, as represented in Figures 6 and 7, this facing being also slit as shown at 28 for providing a pair of loops 29 near the tapered end portions of the pad 25. This enables another pad or filler element 30 to be detachably secured to the outer face of the pad or filler element 25, by engagement of the tapered ends of the pad 30 within the loops 29, as will be found illustrated in Figure 10 of the drawings. Obviously, this pad or filler element 30 might also be provided with a facing providing loops 29 for the attachment of still another pad or filler if the conditions being treated required it, as will be readily understood. It is con-

templated that the pad or filler element will be made of any suitable material affording the desired firmness as well as resiliency such as leather, felt, cork or sponge rubber or any combination of these materials.

It is also proposed to treat all of these parts in such a manner as to render them noiseless while in use, at which time there is, of course, more or less play or rubbing of the parts one upon the other.

Beneath the forward end portion of the flap 20, is adapted to be positioned a pad or filler element 32 (see Figures 1 and 4), which element 32 may be provided in any number and range of sizes for the purpose of treating either one or more of the metatarsal bones of the foot; and for retaining the pad 32 in the proper position for this purpose, as well as permitting the interchange of pads 32 as required, a suitable pin 34 or peg 34 may be employed for attaching the same to the upper face of the insole member 14, as illustrated in Figure 4.

The insole member 14 is provided with a loop 35 suitably secured to the under face thereof at about midway the length of said insole, and at its rear end the insole 14 is provided with a pair of notches 35 cut into the edges of the insole at opposite sides of its heel-seat portion 18 (see Figures 1, 3, 85 and 11 to 13). This loop and notch structure is for the purpose of removably attaching any one of a series of bottom pads or filler members 36 to the under face of said insole member, and at either side of its heel portion. As shown in Figure 11, each pad or filler element 36 is of elongated form, having its rear end or portion of approximately the size and shape of the heel end of the insole 14, and provided with a skived portion 105 37 adapted to be fitted within either of the notches 35 of the insole according as the pad or filler 36 is applied to one side of the insole or the other. The other or forward end of the pad or filler 36 is provided with a longitudinal slit 38, whereby the filler is provided with a finger 39 adapted to extend centrally of the insole 14 and through its loop 35 for either position of the pad 36 with reference to the sides of the insole 14. 110 In Figure 11 of the drawing, the pad or filler element 36 is illustrated in full lines as applied to the outer edge of the insole 14, with its skived portion 37 engaged with the notch 35 of the insole on the opposite side of the heel portion, while in broken lines in said view, the said pad or filler element is represented as attached in position along the inner side of the insole with its skived portion 37 in engagement with the other notch 35 115 of the insole. Thus the said pad or filler element may be interchangeably applied in either of the positions illustrated for bracing either side of the foot, and particularly its heel portion, according to requirements. 120 125 130

These filler elements 36 may be made of any material suitable for the purpose, but in practice, I prefer to make the same of light, strong, metal for firmly yet yieldingly bracing the arch structure at the sides; the thickness of the filler element 36 is chosen to suit the conditions, and where required an extra thickness of material, as indicated at 33 in Figures 5 and 11, may be applied to the outer edge of the filler element, while the heel end of said element may be made relatively thinner, if need be, as shown in Figure 4, so that a higher degree of lifting action is imparted to the longitudinal arch portion of the device.

In Figure 12 of the drawing, I illustrate one of the filler elements 36 as provided with a transverse loop 40, the broken lines in said figure showing the changed position of this filler element 36 with its loop, in the same manner as the changes described in Figure 11. This loop element 40 enables a still further filler element 36' to be applied in superposed relation to the first filler element 36, the said element 36' being also provided with a slit 38 providing a finger 39 for insertion through the loop 40 which is engaged with said finger 39 by being passed through the slit 38 of the filler element 36' as illustrated in Figure 13. The broken lines in Figure 13 illustrate the parts as shifted to the opposite side of the insole member 14, this of course being accomplished by turning the parts 36 and 36' up-side-down in their changed position in the same manner as already described with reference to Figures 11 and 12, the filler element 36' retaining its superposed position with reference to the other filler element 36; or, if desired, under certain conditions, the filler element 36' may be retained at one side of the insole 14 while the other filler element 36 is shifted to the opposite side of the insole, as will be clearly understood.

A practical and efficient construction is thus provided for carrying out the desired objects of the invention. By so adjusting the parts, and using such of the filler elements or as many of them as may be required, a correcting action may be exerted at any and all necessary points for the proper support of either the heel, arch or metatarsal portions of the foot. It is not contemplated, of course, that all of the described filler elements will be likely to be used or required for any one case of treatment, but the improved construction provides practically the widest possible range of adjustment for meeting not only cases of very mild foot trouble, but also those severe cases requiring an unusual degree of bracing or supporting action to be applied to the broken down or weakened portions of the foot. It is to be understood that the filler devices 25, 30, 36 and 36' of course, will be made in assorted

sizes, as well as different thicknesses, for carrying out the adjusting function, and in this connection, it may be remarked that the filler devices 36 and 36' are of course adapted for use, if desired, between the insole and its flap member 20, but these exercise their proper function more effectively when used in the manner described and illustrated.

While I have illustrated and described what I now regard as the preferred form of embodiment of the proposed improvements, I desire to reserve the right to make such changes or modifications as may fairly fall within the scope of the following claims.

What I claim is:

1. An arch support comprising an insole provided with a flexible flap having a marginal connection with the insole, and a filler element adapted to be interposed between said flap and insole, said flap being provided with retaining pockets for removable engagement with the ends of said filler element.

2. An arch support comprising an insole provided with a flexible flap having a marginal connection with the insole, a filler element removably connected with the under face of said flap, and a second filler element removably attached to the under face of said first element.

3. An arch support comprising an insole provided with a flexible flap having a marginal connection with the insole, a filler element removably connected with the under face of said flap, and a second filler element adapted to be applied to the under face of said first element, said first element being provided with retaining loops for removable engagement with the ends of said second element.

4. An arch support comprising an insole provided with a flexible flap having a marginal connection with the insole, a filler element adapted to be interposed between said flap and insole, said flap being provided with retaining pockets for removable engagement with the ends of said filler element, and a second filler element adapted to be applied to the under face of said first element, said first filler element being provided at points slightly removed from the ends thereof with retaining loops for removable engagement with the ends of said second element.

5. An arch support comprising an insole, and a filler element adapted to be removably applied to the under face of said insole, said insole being provided with a notch and a loop for removable engagement with different portions of said filler element.

6. An arch support comprising an insole, and a filler element adapted to be removably applied to the under face of said insole, and provided with a skived portion and a finger portion, said insole being provided with a

notch and a loop for removable engagement with said skived and finger portions respectively, of said filler element.

7. An arch support comprising an insole, 5 and a filler element adapted to be removably applied to the under face of said insole, said insole being provided with a pair of notches and with a loop for removable engagement with different portions of said filler element, 10 said filler element being adapted to be engaged interchangeably with said notches for retaining said element in position at either of the sides of said insole.

8. An arch support comprising an insole, 15 and a filler element adapted to be removably applied to the under face of said insole and formed with a skived portion at one end and with a finger portion at its other end, said insole being provided with a pair of 20 notches at opposite sides of its heel portion and with a loop forward of said notches

adapted for removable engagement with said finger portion, said notches being adapted to be engaged interchangeably with said skived portion of the filler element for retaining the latter in position at either of the sides of said insole. 25

9. An arch support comprising an insole, a filler element for attachment to the under face of said insole, and provided with a retaining loop, means for removably securing said element to the under face of said insole at either of the sides thereof, and a second filler element adapted to be removably applied to the outer face of said first element in either of the positions thereof and provided with a finger portion for retaining engagement with said loop. 30 35

In witness whereof I hereto affix my signature.

HARVEY B. KENNEDY.
